UNITED STATES PATENT OFFICE.

ERNEST HAUSBERG, OF DES MOINES, IOWA.

ELECTRIC TYPE-WRITER.

1,156,288.

Specification of Letters Patent. Patented Oct. 12, 1915.

Application filed October 12, 1909. Serial No. 522,413.

To all whom it may concern:

Be it known that I, ERNEST HAUSBERG, a citizen of the United States, residing at Des Moines, in the county of Polk and State 5 of Iowa, have invented a certain new and useful Electric Type-Writer, of which the following is a specification.

The objects of my invention are to provide a typewriter that may be operated at high 10 speed, and having a light touch, and also to provide means whereby any pressure upon a key whether light or heavy will operate the corresponding type bar to print uniformly.

15 A further object is to provide a typewriter of the class in which the type bars are operated electrically so arranged that the device may be assembled in a compact manner to occupy a minimum of space.

20 A further object is to provide a machine of this kind having a selective magnet for each key and an independent magnet for operating the universal bar operating device, said magnets being so arranged as to 25 be operated by power from a single source of supply such, for instance, as that furnished in an ordinary electric lamp circuit.

A further object is to provide simple and 30 inexpensive means for operatively connecting the various armatures of the selective magnets with the universal operating bar whereby the hooks carried by the various magnets may be made to engage with the universal bar and to disengage therefrom 35 with a minimum of friction and without danger of having said hooks held in frictional engagement with the universal bar.

A further object is to provide a typewriting machine with automatic actuating devices whereby when a circuit is established 40 through any of the selective magnets, the contact devices that control the magnet that operates the universal bar will be held in contact with each other until the printing 45 stroke has been completed so that the operator need not hold the key depressed until the completion of the type bar stroke.

50 My invention consists in certain details, in the construction, arrangement and combination of the various parts of the device, whereby the objects contemplated are attained, as hereinafter more fully set forth,

pointed out in my claims and illustrated in the accompanying drawings, in which—

Figure 1 shows a vertical, central, sectional view of a typewriter embodying my invention. Fig. 2 shows a top or plan view of same with the carriage removed and parts of the operating mechanism broken away to illustrate the details of the construction. 60 Fig. 3 shows a diagram illustrating the electrical features involved in my invention. Fig. 4 shows an enlarged detail view illustrating the means for automatically latching and releasing the circuit closing device 65 of the magnet that operates the universal bar. Fig. 5 shows an enlarged detail side view illustrating the means for operating the end of the rock shaft of the circuit closing arm for the type bar operating magnet, and Fig. 6 shows an enlarged, detail side view of part of the universal bar, to illustrate the means for returning said bar to a normal position and for limiting its movement. 70

75 Referring to the accompanying drawings, I have used the reference numeral 10 to indicate the frame of the machine and 11 a sliding carriage thereon containing a printing platen 12.

80 At the front of the machine is a set of key bars 13 slidably mounted for vertical movement and provided with insulating tips 14 at their lower ends. Each of said key bars has its insulating tip 14 resting upon 85 a spring 15 which spring is fixed to an insulated cross bar 16 and extends under the insulating tip 14. All of said springs 15 normally stand in position slightly elevated 90 above the cross rods 17, which rods are attached at their ends to the bars 18, and said bars are connected with an electrical conducting wire 19, said bars 18 being insulated from the side of the frame by the insulating blocks 20 as shown in Fig. 2. Each of the 95 springs 15 is electrically connected with a conductor wire 21 and the arrangement of the key bars is such that when any one of them is depressed even to the slightest extent, the spring 15 will engage the adjacent 100 rod 17 and thus establish a circuit from the conductor wire 19 to the conductor wire 21 that is connected with the spring 15 of the depressed key. By this arrangement it is

obvious that the up and down movement of the key bar may be comparatively slight, and all of the pressure that need be overcome in depressing the key bar is that sufficient to overcome the resistance of the spring 15. Each one of the conductor wires 21 is connected to a selective electromagnet 22. These electromagnets are intended only for the purpose of attracting an armature with sufficient force to establish an electric circuit by moving a contact arm downwardly against the stationary contact plate, and also to move a selective hook downwardly a short distance to engage with the universal operating bar. Said magnets however do not perform any function of moving the type bars. Therefore each of said magnets 22 may be made comparatively small and I have arranged them to occupy a minimum of space by placing them in two parallel rows transversely of the machine frame, the magnets in one row being arranged in staggered positions with relation to those in the other row as shown in Fig. 2.

25 For each of the magnets 22, I have provided an armature 23. These armatures are pivoted to the rods 24 which extend transversely of the machine frame, and said armatures extend in directions opposite from each other over their respective magnets as shown in Fig. 1. Attached to the outer end of each armature is an open link 25 and said link is arranged to receive a short arm 26 formed on a lever 27. This lever is pivoted to a rod 28 extended across the machine frame. The end of the arm 27 opposite from its pivotal point is pivoted to an upwardly projecting arm 29 having a hook 30 at its upper end. A flat spring 31 is fixed to each of the arms 27 and is arranged to engage a cross rod 32 to yieldingly hold the free end of the arm 27 in an elevated position. The arrangement of these parts is such that when the armature is attracted to its magnet the hook 30 will be moved downwardly and when the armature is released from its magnet the spring 31 will return the hook 30 to its elevated position. By means of the link 25 I have provided a connection by means of which the armature may be elevated by its spring 33 independent of the upward movement of the arm 27, for purposes hereinafter made clear. I have also provided means whereby a downward movement of any one of the armatures 23 will operate to close a circuit through a magnet for operating the printing mechanism as follows: Pivoted to the rods 24 at the opposite sides of the machine frame are two arms 34 extended in opposite directions. Attached to the outer ends of each pair of said arms 34 is a rod 35 which rod lies directly under the free ends of the armatures 23, the arrangement being such that 60 when any armature is depressed, said rod will also be lowered. Connected with each of the arms 34 at one side of the frame is a link 36 extended upwardly and pivotally connected to an arm 37, which arm is pivoted at 38 and is provided with a spring 39, 70 projecting between the stationary pins 40 to normally hold the arm 37 in a substantially horizontal position. Connected to the end of the arm 37 opposite from the spring is an electric contact plate 41 and attached to the 75 said plate is a conductor wire 42. Below the contact plate 41 is a stationary contact plate 43, to which the conductor wire 44 is connected. By this arrangement it is obvious that when any armature 23 is moved 80 downwardly in one of the rows, the arm 34 that is provided for said row will be moved downwardly until the plates 41 and 43 form an electrical contact and when the current through the selective magnet is broken, the 85 spring 39 will cause the arm 34 to return to its normal position and break the contact between the plates 41 and 43. In order that both ends of the rod 35 may move in unison, I have provided at the end of said rod 90 opposite from the arm 36, a corresponding arm 45 shown in Fig. 5 and connected at its upper end to a short lever 46 which lever is fulcrumed to the screw 47 attached to the frame, and a spring 48 is provided for the 95 lever 46 to operate in a manner similar to the spring 39. By this arrangement the ends of the rod 35 are moved up and down in unison although there is only one arm 37 that carries the contact plate and in this 100 connection it is to be understood that there is an arm 37 and a set of contact plates provided for the row of magnets 22 at the rear, the same as for the front row of magnets. It is important that the contact plates 41 105 and 43 be held in engagement with each other until the type bar has been actuated for printing, otherwise if the contact plate 41 should break contact prior to the completion of the printing stroke, the device 110 would not operate effectively.

In order to avoid the necessity for retaining the fingers upon the key bars and to insure the completion of the type bar stroke each time that a key bar is depressed, I have provided the following device: Arranged between the adjacent ends of the arms 37 are two flat springs 49 having inclined faces 50 at the upper ends with shoulders 51. At an intermediate point of each of said flat 115 springs is a lever 52 fulcrumed at 53 and provided with an upwardly projecting arm 54 which arm is connected to a rod 55 having a lug 56 thereon. A guide rib 57 is provided for slidably supporting the rod 55. The arrangement of these parts is such that when the arm 54 is in position as shown in Fig. 4, and the arm 37 is depressed, then it 120 will engage the inclined face 50 and force the upper end of the spring 49 rearwardly. 125

until it passes below the shoulder 51 whereupon said shoulder will prevent any upward movement of the arm 37 and will hold the contact bar 41 against the plate 43, and this 5 will be continued until the arm 54 is moved rearwardly at its upper end which will have the effect of moving the upper ends of the springs 49 toward each other to release the arms 37 from their shoulders 51.

10 The mechanism for actuating the type bars comprises an electromagnet 58. An armature 59 is provided for said magnet and is supported by hanger arms 60 at its ends. Connected with each end of the armature 59 is a rod 61 which rod is operatively connected to the universal operating bar. This operating bar comprises two upwardly extended arms 62 pivoted at their lower ends to the sides of the machine frame 20 and extended upwardly, and having a bar proper 63 attached to their upper ends. This bar extends across the machine and normally stands in position under the hooks 30 as clearly shown in Fig. 1. One of said 25 arms 62 is arranged in position adjacent to the lug 56, the object being to provide means whereby, when said arm 62 is moved rearwardly, it will strike the lug 56 when at the rear limit of its movement and thus cause 30 the springs 49 to release the arms 37. In order to provide for yieldingly holding this universal bar 63 at its forward limit of movement in position where it will be directly under the hooks 30, I have attached 35 thereto a spring 70 and I have also provided a limiting stop 71 to be engaged by the bar when at its forward limit of movement. This spring also serves the function of normally holding the armature 59 away from 40 its magnet 58.

I have previously explained the means for lowering any particular one of the hooks 30 by pressing upon the corresponding key bar, and also the means whereby a 45 circuit is completed through the conductor wire 44 when any one of said hooks is lowered. The completion of this circuit obviously magnetizes the electromagnet 58 and attracts the armature 59, and this will have the effect of moving the universal operating bar rearwardly; in this way the selected one of the hooks 30 is also moved rearwardly. The pivotal center of said universal bar and the pivotal centers of said 50 hooks are arranged adjacent to each other and also in such a manner that when said hooks are moved to position in engagement with the universal bar the pivotal point of said hook and the pivotal point of the universal bar will be in line with each other so that they will move rearwardly together and not bind and so that the hook may readily be released when the universal bar reaches its forward limit of movement. To 55 provide means whereby this rearward move-

ment of the selected one of the hooks 30 is caused to operate the corresponding type bar, I have provided a series of upright levers 64 fulcrumed to a cross rod 65. Pivoted to the upper end of each lever 64 is a short link 66 which in turn is pivoted to a lug 67 on a type bar 68 which latter is fulcrumed at 69 so that the type thereon will strike against the platen 12. By this construction it is obvious that when the universal operating bar is moved rearwardly at the time any of the hooks 30 is at its downward limit, the corresponding type bar will be moved to printing position, and at the time when the bar 63 is at its rearward 70 limit, the locking device for the circuit closing device will be released.

75 Referring to the diagram of the electrical parts of the device illustrated in Fig. 3, I have used the reference numeral 72 to indicate a dynamo or other source of electrical supply. In the conductor wire 73 leading from the dynamo is a resistance 74 and a conductor wire 75 is connected with the conductor wire 73 beyond the resistance 74 80 and leads to the conductor wires 42 which are designed for establishing the circuit through the large magnet 58. After passing through said magnet the current returns by means of the conductor wire 76. 85 The circuit for the selective magnets is connected with the conductor wire 73 beyond the resistance 74 by means of the conductor wire 77 and in this circuit is a second resistance 78 to which the conductor wire 19 90 is connected. The conductor wires 21 lead to the selective magnets and the conductor wires 79 lead from the selective magnets and return through the conductor wire 80 with which they are electrically connected. By this arrangement it is obvious that by means of an electric current taken from a source of supply, an independent circuit may be provided for 95 operating both the selective magnets and the printing magnet as the various resistance devices applied to the different circuits are so arranged that the voltage of the current as applied to the selective magnets is reduced to such an extent as to provide a current sufficient for the purpose of the smaller selective magnets while, at the same time, providing a sufficient current of 100 higher voltage for the purpose of operating the printing magnet.

105 In practical operation the operator depresses one of the key bars. The pressure he applies may be either light or heavy and the key bar need only be depressed far enough to bring the spring 15 against the 110 rod 17. In this way an electric circuit is established through the proper selective magnet which results in attracting the armature 23. This moves the lever 27 downwardly and also the hook 30. At the same 115 120 125 130

time it moves the arm 37 downwardly and establishes a circuit through the universal magnet. Obviously the selective magnets can be comparatively small for the reason that the only function they perform is to move the hooks 30 and the arms 37 downwardly which may both be done without overcoming any material amount of friction or resistance. The contact made by the operator upon the key bar need not be continued longer than is necessary to establish a circuit through the selective magnet for the reason that the plates 41 and 43 are locked in contact by means of the springs 49. When a circuit is established through the universal magnet its armature is attracted and the universal operating bar 63 is moved rearwardly and carries with it the selective type bar. Inasmuch as the same magnet is used for operating all of the type bars, it is obvious that each will strike upon the platen with the same amount of force so that the printing will be uniform in character. During the completion of the rearward movement of the universal bar 63, the locking device for the circuit closing device is released, so that the circuit of the universal magnet is broken when the type bar is released, and as soon as the circuit is broken the universal bar 63 is returned to a normal position by means of the spring 70. During the operation of the device the type bar is held in printing position until the key bar is released, and as soon as the key bar is released after the completion of the printing stroke the circuit is broken and the universal bar is returned and at the same time the hook is released from it. In this connection I have provided for insuring the release of the hooks 30 from the universal bars 63 upon the release of the key bar as follows: The connection between the armatures 23 and the levers 27 is by means of a link 25 which permits the armature 23 to move upwardly while the lever 27 is stationary. If the said connection between the lever 27 and armature 23 were rigid, then so long as the hook 30 is held down to the bar 63, the lever 27 would also be held down, which would result in holding down the rod 35 and with it the arm 37 so that the circuit would be maintained through the universal magnet, but by having the sliding connection by means of a link 25 the armature 23 may move upwardly and break the circuit thus releasing the universal bar and permitting the lever 27 to be moved upwardly by its spring.

It is obvious that the arrangement of the selective magnets and other parts of the device is such that the entire machine may be made in compact form to occupy a minimum of space. Another advantage gained by my improved construction is that I am enabled to employ type bars of the class now com-

monly used on visible type writers and to operate these type bars by means of selective magnets arranged in a straight row across the machine and also to so arrange the parts that the armatures of the selective magnets are moved directly toward and from the selective magnets and do not have any rubbing or friction between them and the selective magnets when the power magnet is being operated.

75

I claim as my invention—

1. In a device of the class described, the combination of key bars, type bars, a selective electromagnet for each key bar, means for establishing an electric circuit through the corresponding electromagnet upon a depression of a key bar, a selective armature for each electromagnet, a circuit closing device connected with and operated by each selective armature, a type bar operating electromagnet, means operated by said circuit closing device for establishing an electric circuit through it when any one of said circuit closing devices is in closed position, an armature for said magnet, a universal bar operatively connected with the said armature, and means interposed between the selective armatures and the type bars for operatively connecting a type bar to the universal bar when the corresponding selective armature is operated.

2. In a device of the class described, the combination of key bars, type bars, a selective electromagnet for each key bar, means for establishing an electric circuit through the corresponding electromagnet upon a depression of a key bar, a selective armature for each electromagnet, a circuit closing device operatively connected with each selective armature, a type bar operating electromagnet, means for establishing an electric circuit through it when any one of said closing device is operated, an armature for said magnet, a universal bar operatively connected with the said armature, and means interposed between the selective armatures and the type bars for operatively connecting a type bar to the universal bar when the corresponding selective armature is operated, and means for locking said circuit closing device for a limited time in closed position.

3. In a device of the class described, a key bar, a selective electromagnet, means actuated by the key bar for establishing an electric circuit through the selective magnet, a selective armature for the magnet, a circuit closing device connected with and operated by the selective armature, a type bar, a type bar operating electromagnet, means for establishing an electric circuit through it by means of said circuit closing device, a type bar operating armature for said magnet, and means operated by the type bar operating armature for actuating the type bar

120

125

130

bar when the said armature is attracted to its magnet.

4. In a device of the class described, a key bar, a selective electromagnet, means actuated by the key bar for establishing an electric circuit through the selective magnet, a selective armature for the magnet, a circuit closing device operatively connected with the selective armature, a type bar, a type bar operating electromagnet, means for establishing an electric circuit through it by means of said circuit closing device, a type bar operating armature for said magnet, and means operated by the type bar operating armature for actuating the type bar when the said armature is attracted to its magnet, and means for automatically locking the said circuit closing device for a limited time in closed position.
5. In a device of the class described, a key bar, a selective electromagnet, means actuated by the key bar for establishing an electric circuit through the selective magnet, a selective armature for the magnet, a circuit closing device operatively connected with the selective armature, a type bar, a type bar operating electromagnet, means for establishing an electric circuit through it by means of said circuit closing device, a type bar operating armature for said magnet, and means operated by the type bar operating armature for actuating the type bar when the said armature is attracted to its magnet, and means for automatically locking the said circuit closing device for a limited time in closed position.
6. A device of the class described, comprising a series of key bars, a selective electromagnet for each key bar, means for establishing an electric circuit through one of said electromagnets upon a depression of the corresponding key bar, a selective armature for each selective electromagnet, a circuit closing device, means operated by the armatures for closing the circuit closing device when any of said armatures is attracted to its magnet, a universal magnet, an armature therefor, a universal bar operatively connected with said armature, means operated by the said circuit closing device for establishing an electric circuit through the universal magnet, a hook for each selective armature operatively connected therewith to be moved into operative relation to the universal bar when the selective armature is moved toward its magnet, and a type bar for each of said hooks operatively connected therewith.
7. A device of the class described, comprising a series of key bars, a selective electromagnet for each key bar, means for establishing an electric circuit through one of said electromagnets upon a depression of the corresponding key bar, a selective armature for each selective electromagnet, a circuit closing device arranged to be operated when any of said armatures is attracted to its magnet, a universal magnet, an armature therefor, a universal bar operatively connected with said armature, means operated by the said circuit closing device for establishing an electric circuit through the universal magnet, an armature therefor, a universal bar operatively connected with said armature, means operated by the said circuit closing device for establishing an electric circuit through the universal magnet, a hook for each selective armature, operatively connected therewith to be moved into operative relation to the universal bar when the selective armature is moved toward its magnet, and a type bar for each of said hooks operatively connected therewith, the connection between each selective armature and its hook including means for permitting the armature to move away from its magnet during the time that the hook remains in engagement with the universal bar to thereby permit the circuit closing device to open.
8. A device of the class described, comprising a series of key bars, a selective electromagnet for each key bar, means for establishing an electric circuit through one of said electromagnets upon a depression of the corresponding key bar, a selective armature for each selective electromagnet, a circuit closing device arranged to be operated when any of said armatures is attracted to its magnet, a universal magnet, an armature therefor, a universal bar operatively connected with said armature, means operated by the said circuit closing device for establishing an electric circuit through the universal magnet, a hook for each selective armature operatively connected therewith to be moved into operative relation to the universal bar when the selective armature is moved toward its magnet, and a type bar for each of said hooks operatively connected therewith, the connection between each selective armature and its hook including means for permitting the armature to move away from its magnet during the time that the hook remains in engagement with the universal bar to thereby permit the circuit closing device to open, and a spring for normally holding the circuit closing device in open position.
9. A device of the class described, comprising a series of key bars, a selective electromagnet for each key bar, means for establishing an electric circuit through one of said electromagnets upon a depression of the corresponding key bar, a selective armature for each selective electromagnet, a circuit closing device arranged to be operated when any of said armatures is attracted to its magnet, a universal magnet, an armature therefor, a universal bar operatively connected with said armature, means operated by the said circuit closing device for establishing an electric circuit through the universal magnet, an armature therefor, a universal bar operatively connected with said armature, means operated by the said circuit closing device for establishing an electric circuit through the universal magnet, a hook for each selective armature, operatively connected therewith to be moved into operative relation to the universal bar when the selective armature is moved toward its magnet, and a type bar for each of said hooks operatively connected therewith, the connection between each selective armature and its hook including means for permitting the armature to move away from its magnet during the time that the hook remains in engagement with the universal bar to thereby permit the circuit closing device to open, and a spring for normally holding the circuit closing device in open position.

versal magnet, a hook for each selective armature operatively connected therewith to be moved into operative relation to the universal bar when the selective armature is moved toward its magnet, and a type bar for each of said hooks operatively connected therewith, the connection between each selective armature and its hook including means for permitting the armature to move away from its magnet during the time that the hook remains in engagement with the universal bar to thereby permit the circuit closing device to open, a spring for normally holding the circuit closing device in open position, and means for automatically locking the circuit closing device in its closed position.

10. A device of the class described, comprising a series of key bars, a selective electromagnet for each key bar, means for establishing an electric circuit through one of said electromagnets upon a depression of the corresponding key bar, a selective armature for each selective electromagnet, a circuit closing device arranged to be operated when any of said armatures is attracted to its magnet, a universal magnet, an armature therefor, a universal bar operatively connected with said armature, means operated by the circuit closing device for establishing an electric circuit through the universal magnet, a hook for each selective armature operatively connected therewith to be moved into operative relation to the universal bar when the selective armature is moved toward its magnet, and a type bar for each of said hooks operatively connected therewith, the connection between each selective armature and its hook including means for permitting the armature to move away from its magnet during the time that the hook remains in engagement with the universal bar to thereby permit the circuit closing device to open, a spring for normally holding the circuit closing device in open position, and means for automatically locking the circuit closing device in its closed position, and means for automatically releasing said locking device, at the end of the type bar stroke.

11. In a device of the class described, the combination of key bars, type bars, a selective electromagnet for each key bar, means for establishing an electric circuit through the corresponding electromagnet upon a depression of a key bar, a selective armature for each electromagnet, a circuit closing device operatively connected with each selective armature, a type bar operating electromagnet, means for establishing an electric circuit through it when any one of said closing devices is operated, an armature for said magnet, a universal bar operatively connected with the said armature, and means inter-

posed between the selective armatures and the type bars for operatively connecting the type bar to the corresponding selective armature when the universal bar is operated, a single source of electrical supply for the selective magnets and the universal magnet, conductor wires leading from the source of electrical supply to said magnets and arranged to permit the flow of electricity to any of the selective magnets or to the universal magnet at the same time.

12. A device of the class described, comprising a series of key bars, a selective electromagnet for each key bar, means for establishing an electric circuit through each magnet upon a depression of the corresponding key bar, a spring controlled armature for each selective magnet, a spring controlled lever for each of said armatures, means for providing a limited sliding connection between each of said armatures and its lever, a hook connected with each lever, a type bar operatively connected with each hook, a circuit closing device, a spring for normally holding same in open position, means actuated by any one of said selective armatures for closing said circuit closing device, a universal magnet, means operated by the circuit closing device for establishing a current of electricity through the universal magnet, an armature for the universal magnet, a universal bar operatively connected with said armature and disposed adjacent to said hooks, the parts being so arranged that when any selective armature is operated the corresponding hook will engage the universal bar and then the universal armature when attracted to its magnet will operate the universal bar and said hook to actuate the corresponding type bar.

13. A device of the class described, comprising a series of key bars, a selective electromagnet for each key bar, means for establishing an electric circuit through each magnet upon a depression of the corresponding key bar, a spring controlled armature for each selective magnet, a spring controlled lever for each of said armatures, means for providing a limited sliding connection between each of said armatures and its lever, a hook connected with each lever, a type bar operatively connected with each hook, a circuit closing device, a spring for normally holding same in open position, means actuated by any one of said selective armatures for closing said circuit closing device, a universal magnet, means operated by the circuit closing device for establishing a current of electricity through the universal magnet, an armature for the universal magnet, a universal bar operatively connected with said armature and disposed adjacent to said hooks, the parts being so arranged that when any selective armature is operated the

- corresponding hook will engage the universal bar and then the universal armature when attracted to its magnet will operate the universal bar and said hook to actuate the universal bar and the pivotal center of the universal bar will be in line with each other, for the purposes stated. 65
- 5 16. In an electrically operated typewriter, the combination of keys, type bar devices, a series of selective magnets energized by a depression of the keys, means operated by a selective magnet for placing a type bar device in operative position, a universal magnet for moving the type bar devices from operative position to printing position, a circuit closing device operated upon the depression of a key, and means operated by the selective magnet for automatically energizing the universal magnet. 70
- 10 17. In a device of the class described, the combination of keys, a selective magnet for each key, an electric circuit for each of said selective magnets, means for closing the circuit through a corresponding selective magnet when a key is depressed, type bars, a type bar operating device for each type bar, means actuated by a selective magnet, when its circuit is closed, for moving the type bar operating mechanism of a corresponding type bar to operative position, a type bar operating magnet, a separate electric circuit therefor, an armature for said magnet, means operated by said armature for actuating a type bar operating device when the latter has been moved to operative position, and means actuated upon and by the closing of the circuit of any selective magnet for closing the separate circuit of the type bar operating magnet. 80
- 15 18. In an electrically operated typewriter, the combination of keys, selective magnets, means for establishing a circuit through a corresponding selective magnet when a key is depressed, type bars, a type bar operating device for each type bar, means actuated by a selective magnet for moving the type bar operating mechanism of a corresponding type bar to position for operation upon the completion of a circuit through the selective magnet, a universal magnet, an armature for same, means operated by said armature for operating a type bar operating device when the latter has been moved to position for being operated, a circuit making and breaking device for the universal magnet, electrically operated means actuated upon the completion of a circuit through any selective magnet for actuating the circuit making and breaking device to close a circuit through the universal magnet, and means for holding the circuit making and breaking device in its closed position, said means being automatically released by the movement of the armature toward the universal magnet. 90

- means operated by a selective magnet for placing a type bar device in operative position, a universal magnet for moving the key bar devices to printing position, a single circuit closing device operated upon the depression of a key, and means operated by the closing of a circuit through a selective magnet for automatically establishing a circuit through the operating magnet.
- 10 20. In an electrically operated typewriter, the combination of keys, type bar devices, a series of selective magnets, means for energizing them upon a depression of the keys, means operated by a selective magnet for placing the type bar device in position to be operated, a universal magnet for moving the type bar devices from operative position to printing position, and means operated by the selective magnet for energizing the universal magnet.
- 15 21. In an electrically operated typewriter, the combination of a series of type bars pivotally supported and capable of striking at a common center, an operating device for each type bar comprising a pivoted arm operatively connected with the type bar, a hook supported for longitudinal and pivotal movement, means for connecting the hook with said arm, keys, means operated upon the depression of a key for moving the corresponding hook longitudinally, a universal magnet, a universal bar operatively connected with the magnet and designed to be engaged by said hook to thereby move said hook on its pivot in the direction required for imparting a striking movement to the corresponding type bar.
- 25 22. In an electrically operated typewriter, the combination of a series of type bars pivotally supported and capable of striking at a common center, an operating device for each type bar, comprising a pivoted arm operatively connected with the type bar, a hook supported for longitudinal and pivotal movement, means for connecting the hook with said arm, keys, a circuit closer for each key, a selective magnet for each circuit closer, an armature for each selective magnet, means for connecting each armature with said hook arranged to move the hook longitudinally upon the movement of the armature toward the magnet, a universal magnet, a universal bar operatively connected with the universal magnet and designed to be engaged by said hook to thereby move said hook on its pivot in the direction required for imparting a striking movement to the corresponding type bar.
- 30 23. In an electrical typewriter, the combination of a series of type bars, the pivotal supports of which are arranged on a line extended transversely of the machine and curved upwardly toward the sides thereof, whereby the type bars will all strike a common printing center, an operating device for each type bar comprising a hook mounted for longitudinal and pivotal movement, means for connecting the hook with a type bar, whereby a pivotal movement of the hook will operate the type bar, keys, means whereby, upon the depression of a key, the corresponding hook will be moved longitudinally, a universal magnet, a universal bar operatively connected with the magnet, said parts being so arranged that when a hook is moved longitudinally and the universal magnet operated the hook will cause the corresponding type bar to be operated.
- 35 24. In an electrically operated typewriter, the combination of keys, a series of selective magnets, means for establishing a circuit through a selective magnet by the depression of a corresponding key, an armature for each selective magnet, type bars, an operating device for each type bar comprising a hook capable of longitudinal and pivotal movement, means for connecting each hook with a selective magnet whereby, when the selective magnet is energized the hook will be moved only in a longitudinal direction, means for connecting each hook with a type bar, a universal magnet, a universal bar operatively connected with the universal magnet and designed to be engaged by said hooks, said parts being so arranged that when the universal bar is moved the hook will be given a pivotal movement only and the corresponding type bar will be operated without affecting the relation between the corresponding selective magnet and its armature.
- 40 25. In an electrically operated typewriter, the combination of keys, type bars, a selective electromagnet for each key, means for establishing an electric circuit through a selective magnet upon the depression of the corresponding key, a type bar operating device for each type bar, means operated by the selective magnet for moving said type bar operating device to position for being operated upon the depression of a corresponding key, a universal magnet, a circuit establishing and breaking device for the universal magnet, electrically operated means automatically actuated upon the completion of a circuit through the selective magnet for actuating the circuit making and breaking device to close the circuit through the universal magnet, an armature for the universal magnet, and means actuated by said armature for operating the type bar operating device of the type bar corresponding to the particular selective magnet through which a circuit has been established.
- 45 26. In an electrically operated typewriter, the combination of keys, selective magnets, means for establishing a circuit through a corresponding selective magnet when the key

- is depressed, type bars, a type bar operating device for each type bar, means actuated by a selective magnet for moving the type bar operating mechanism of a corresponding 65
- 5 type bar to position for operation upon the completion of a circuit through the selective magnet, a universal magnet, an armature for same, means operated by said armature for operating a type bar operating device when 70
- 10 the latter has been moved to position for being operated, a circuit making and breaking device for the universal magnet, and electrically operated means actuated upon and by the completion of a circuit through any selective magnet for closing the circuit making and breaking device to close a circuit 75 through the universal magnet.
27. In an electrically operated typewriter, the combination of keys, selective magnets, 80 means for establishing a circuit through a corresponding selective magnet when the key is depressed, type bars, a type bar operating device for each type bar, means actuated by a selective magnet for moving the
- 25 type bar operating mechanism of a corresponding type bar to position for operation upon the completion of a circuit through the selective magnet, a universal magnet, an armature for same, means operated by said 85
- 30 armature for operating a type bar operating device when the latter has been moved to position for being operated, a circuit making and breaking device for the universal magnet, and electrically operated means
- 35 actuated upon and by the completion of a circuit through any selective magnet for actuating the circuit making and breaking device to close a circuit through the universal magnet, and means for holding the circuit making and breaking device in its 90 closed position, said means being automatically released by the movement of the armature toward the universal magnet.
28. In an electrically operated typewriter, 95 the combination of a series of type bars, the pivotal supports of which are arranged on a line extended transversely of the machine and curved upwardly toward the sides thereof so that the type bars will all strike a common printing center, an operating device for each type bar comprising a pivoted arm operatively connected with the type bar, a hook supported for longitudinal and pivotal movement, means for connecting the hook 100 with said arm, keys, a circuit closer for each key, a selective magnet for each circuit closer, an armature for each selective magnet, means for connecting each armature with said hook arranged to move the hook 105 longitudinally upon the movement of the armature toward the magnet, a universal magnet, an armature therefor, a universal bar operatively connected with said armature and designed to be engaged by said 110
- hook thereby to move said hook on its pivot in the direction required for imparting a striking movement to the corresponding type bar.
29. In an electrically operated typewriter, the combination of a series of type bars pivotally supported and capable of striking at a common center, an operating device for each type bar comprising a pivoted arm operatively connected with the type bar, a hook supported for longitudinal and pivotal movement, means for connecting the hook with said arm, keys, a circuit closer for each key, a selective magnet for each circuit closer, an armature for each selective magnet, means for connecting each armature with a corresponding hook arranged to move the hook longitudinally upon the movement of the armature toward the magnet, a universal magnet, an armature therefor, a universal bar operatively connected with said armature and designed to be engaged by said hook, said parts being so arranged that when the universal bar is moved the hook will be given a pivotal movement only and the corresponding type bar will be operated 115 without affecting the relation between the corresponding selective magnet and its armature.
30. In an electrically operated typewriter of the class employing selective magnets for moving type bar devices to position to be operated and a universal magnet for moving the selective type bar device to printing position, the combination of keys, and means actuated by the closing of a single electrical 120 contact at any of said keys for establishing a circuit through a selective magnet and a separate circuit through the universal magnet.
31. A device of the class described, comprising a series of keys, a selective electromagnet for each key, means for establishing an electric circuit through one of said electromagnets upon a depression of the corresponding key, a selective armature for each 125 selective electromagnet, a rod adjacent to a series of selective armatures and designed to be moved by the movement of any of said selective armatures toward its magnet, means operated by the movement of said rod for closing a circuit closing device, a universal magnet, an armature therefor, a universal bar operatively connected with said armature, means operated by said circuit closing device for establishing an electric circuit through the universal magnet, a hook for each selective armature operatively connected therewith to be moved into operative relation to the universal bar when the selective armature is moved toward its 130 magnet, and a type bar for each of said hooks operatively connected therewith.
32. In an electrically operated typewriter,

the combination of keys, a circuit closer for each key, a series of selective magnets, type bar devices, means actuated by a selective magnet for moving a type bar device to operative position, a universal magnet, means operated by the universal magnet for operating the selected type bar device, and means automatically operated for closing

successive circuits through a selective magnet and the universal magnet.
